UNITED STATES PATENT OFFICE

BERNARDUS LEBUINUS MARIA VAN DER LANDE AND GERRIT KOMEN, OF DEVENTER,
NETHERLANDS

APPARATUS FOR PREPARING CASTING MOLDS

Application filed March 26, 1928, Serial No. 264,918, and in the Netherlands August 27, 1927.

This invention relates to a method and apparatus for preparing molds for casting products of various kinds, more especially flywheels.

5 With the use of sandslinger or other machines serving for the preparing of molds in the casting industry the objection is often experienced that the removal of the sand supply device very greatly fatigues the operator serving the machine and that the frequent adjustments of that supply device over the molding boxes or such like requires much time.

10 The object of the invention is to entirely eliminate this objection and to obtain the great advantage that from $1\frac{1}{2}$ to 4 times larger molding boxes or similar devices are capable of being filled than with the sandslinger or similar machines that are used 15 without the device, which forms the subject of this invention, whilst to obtain the further advantage that the sand is distributed much more evenly in the mold boxes, since this influences the good finish of the castings.

20 25 The accompanying drawings illustrate one constructional example of the device according to the invention, and in which:—

Figure 1 is a part section and a part elevation of the entire device.

30 Figure 2 shows a detail in half section.

Figure 3 is a reverse plan view of said detail.

35 The device forming the subject of the invention consists of a pedestal 1 in which bearing balls 3 are inserted in the raceway 2, so that the upper structure of the device resting upon these balls can be turned as required.

40 The circular bedplate 4 which therefore rests with the central boss 5 and the corresponding raceway 6 upon the balls 3 is rotatable. Attached to the bedplate 4 by bolts 8 are a number of supports 7 and these are replaceable by other supports of various 45 lengths. These supports 7 may be attached in any number and be placed anywhere upon the plate 4, and they carry on their upper ends by means of the bolts 9 a pattern plate 10.

50 In the accompanying drawings, the molding plate has a peculiar construction which is

hereinafter described. As a matter of fact, however, every and any mold plate can be used upon the supports 7.

The mold plate of which the accompanying drawings illustrate an example of the use of 55 the mold serves especially for the casting of flywheels. Hitherto these molds have been prepared by means of sweeps or wooden patterns, and were expensive owing to the long time required for molding, and owing to the 60 fact that they last in use for a comparatively short time. These objections are practically altogether eliminated by the device which forms the subject of the invention.

The pattern plate 10 which forms the bottom of the mold box 21 is combined with a hollow annular casing 11 beneath it, and at certain distances in such hollow casing openings 12 are left. The centre part of the plate 10 carries a series of molding members 13 65 corresponding to the spokes of the flywheel to be cast. The hollow annular member 11 is adapted for the reception of an adjustable ring 14 that forms a die for forming one half of the mold, the ring 14 in this case forming 70 one half of the flywheel rim and being adjustable so that rims of different width may be made.

The adjusting of this ring is effected with the aid of the wire spindle 15 resting upon 75 the pivot 18 in the pedestal 16, this latter being fixed with bolts to the round bedplate 4.

80 By rotating the spindle 15 by means of the hand spokes 17 which may, for instance, be replaced by a handwheel attached by means of a pin to the spindle, the nut 19 on the upper end of the spindle is moved upwards or downwards as desired. Spokes 20 attached to the nut extend radially through the openings 12 of the annulus 11 and are attached to the adjustable ring 14, as is clearly shown in Figure 2.

85 The molding operation is as follows: After the ring 14 has been adjusted with the aid of the hand-operated device 17 to the half of the breadth which is desired for the width of the rim the mold box 21 which may be any shape is placed upon table 10, the sand-pouring device of the sandslinger or similar machine 90

is then arranged above the mold box. The machine is now rotated in any suitable way so that the mold box and pattern plate revolve relatively to the sand-supplying means and while the sand is being fed into the mold box. 5 The operator serving the machine may thus remain in his place and only need adjust the sand supply device over one line and only once from the centre to the edge of the mold box, owing to which, with a definite length of the sand outflow device of the sandslinger or similar machine, much larger articles can be molded while, in addition, work can be performed much more quickly.

10 15 It is clear that the adjustable arrangement given by way of example in the accompanying drawings and numbered 17—15—19—20—14 need not always be introduced upon rotating table (4), that adjustable arrangement can also be constructed upon a fixed foundation. It may also be used for other castings than exclusively for flywheels.

15 20 By the above described method and machine fine and sharp castings are obtained 25 which are absolutely the equivalent of each other, a thing that is extremely desirable for production en masse.

Having now described our invention, what 30 we claim as new and desire to secure by Letters Patent is:—

1. A molding apparatus for the purpose described comprising in combination a pattern plate, a molding box carried thereon, a pattern block carried on a stem concentric with 35 the pattern block, a turntable supporting the pattern plate, molding box and central stem, means for rotating the turntable, and means for rotating the centre stem to adjust the pattern block relatively to the pattern plate to 40 vary the depth of the mold.

2. Molding apparatus as claimed in claim 1, in which one part of the pattern plate comprises a hollow annular casing depending therefrom, and the other part is an annular 45 rib engaging said hollow casing and adjustably carried on a centre stem.

3. Molding apparatus for the purpose described comprising in combination a pattern plate, a molding box carried thereon, a pattern block carried on a stem concentric with the pattern block, a fixed centering member supporting the pattern plate, molding box and central stem, and means for rotating the centre stem to adjust the pattern block relatively to the pattern plate to 50 vary the depth of the mold.

In testimony whereof we have signed our names to this specification.

B. L. M. VAN DER LANDE.
